UNITED STATES PATENT OFFICE.

ARTHUR E. BINNS, OF SOUTH WINDHAM, CONNECTICUT.

GAS-TURBINE ENGINE.

1,099,335.

Specification of Letters Patent.

Patented June 9, 1914.

Application filed November 22, 1911. Serial No. 661,663.

To all whom it may concern:

Be it known that I, ARTHUR E. BINNS, a citizen of the United States, residing at South Windham, Windham county, Connecticut, have invented certain new and useful Improvements in Gas-Turbine Engines, of which the following is a full, clear, and exact description.

My invention relates to gas turbine engines and is concerned with improvements in the general structure of the engine and particularly in the construction and arrangement of the valves for admission of the explosive mixture for operating the engine.

An object of the invention is to provide a plurality of jets for discharging the ignited gas upon the rotor or rotors.

A further object is to provide a simple and effective cam system for actuating the compressing means for the gas, operating synchronously with the operation of the admission valves.

With these and other objects in view, as will appear from the following detailed description of the invention, the latter consists in the construction and arrangement of parts, an embodiment of which is illustrated in the accompanying drawing, in which the figure shows a longitudinal central section of the turbine, illustrating the construction and relative arrangement of the several parts thereof.

In the embodiment of my invention herein selected for illustration, 1 indicates an outer casing of the turbine mechanism, which, as indicated, may be formed in sections of sheet metal secured together as at 2—2. The forward end of the casing is inclosed by head 3 and the opposite end by means of a head 4, which may be formed integrally with the adjacent end section 5 of the outer casing.

A reinforcing and bearing plate 6 may be secured to this head 4 if desired. The turbine casing proper comprises the opposite end sections 7 and 8, preferably of cast metal and an intermediate section 9 also of cast metal. Within the end sections 7 and 8, which may be called compression sections, are arranged the inlet valves and gas compressing mechanisms for supplying fluid pressure to the rotor in the central section 9, which may be called the expansion or rotor section, forming the rotor or expansion chamber. Within suitable bearings 10 and 11, supported by the end sections 7 and 8, is journaled a turbine shaft 12, upon which one

or more rotors 13 and 14 may be fixed. The rotor chamber 9 is provided with heads 15 and 16 having suitable stuffing boxes 17—17 for the passage of the turbine shaft. Within chambers 18 and 19 in the turbine casing sections 7 and 8 respectively, are mounted corresponding piston operating cams 20 and 21. Said cams are of the shape indicated, namely, with one side of greater height than the other and at the periphery of each cam is a channel 22, within which the piston rods 23 of the compression pistons 24 have bearings, the pistons 24 operate in cylinders 25 preferably cast integral in the end casing sections 7 and 8. I have shown these cams 20 and 21 diagrammatically, *i. e.*, as solid, but it is obvious that in practice they will be formed hollow at their higher portions in order to afford equal distribution of mass about the center of rotation. The piston rods 23 are connected by rods 23^a pivoted at each end of said piston rods and immediately pivoted on a non-rotating sleeve 12^a loosely mounted on the turbine shaft 12 and resting against the squared face of the hubs of cams 20 and 21. With this construction, when one of the pistons 24 is moved upwardly by a cam to compress a charge, the opposite piston 23 is moved downwardly through the rod connection 23^a to draw in a fresh charge. Each cylinder has an outlet 26 into an explosion chamber 27 adjacent each cylinder. The inner ends of these explosion chambers are closed by valves 28 operated from the cam disks 29, which in turn are operated by bevel gears 30 and 31, each of the latter being mounted on a shaft 32 upon one extremity of which is mounted a gear 33 meshing with a gear 34, which in turn meshes with gear 35 fixed to the turbine shaft 12.

The timing of the gears 33 to 35 inclusive and of the cam disks 29 is such that the valves 28 are opened exactly at the point of the most effective compression of the gas within the cylinder 25 and the explosion chambers 27. It should be understood that any suitable ignition mechanism, such as electrodes 27', may be mounted within the explosion chamber 27 to explode the charge at the desired point of compression, such electrodes being provided with suitable connections to a source of electric energy and with the usual accessories of a sparking apparatus.

The explosive mixture is supplied to the

cylinders 25 by means of supply pipes 36 connected with a source of supply at 37. Said supply pipe is provided with check valves 38 adjacent each cylinder to prevent the fuel being forced back therethrough, upon compressing movement of the pistons 24, and to prevent ignition of the fuel in said pipes from the explosion of the charge.

In the operation of the turbine, the cams 20 and 21 are rotated by the turbine shaft 12 and the pistons 24 are reciprocated in their cylinders to compress the charges therein. The valve mechanisms are so arranged that the valves 28 open successively just prior to the explosion of the charges in each explosion chamber 27, whereby motive power is supplied to the rotors 13 and 14. The exhaust gases leave the rotor chamber by means of exhaust passage 39.

It will be evident that I have associated in a turbine, spaced compression sections wherein gas is compressed and fired and an intermediate rotor chamber to which the compressed and fired gas is led and in which it expands to operate a rotor. In the drawings I have shown two rotor members rigidly secured to the same shaft, one rotor member for each compression section. It will be understood, of course, that a single rotor may be employed, the compressed and exploded gases from the end compression sections operating against the opposite sides or edges of this rotor member, the firing mechanism being suitably timed.

While I have herein described a particular embodiment of my invention, it is to be understood the same may be altered in detail and relative arrangement of parts within the scope of the appended claims.

What I claim is:—

1. In a gas turbine engine, in combination, a casing having therewithin a rotor chamber, and having at opposite sides of said chamber compression and explosion sections, one of said sections providing an annular series of compression chambers, and a piston for each of said chambers, a shaft within said casing extending through said rotor chamber, a rotor member fixedly carried by said shaft within said rotor chamber, cam members fixedly carried by said shaft at opposite sides of said rotor chamber, operative connections between said cam members and said pistons arranged to operate said pistons to successively compress charges in successive compression chambers, firing electrodes associated with said compression chambers, means for feeding fuel to said compression chambers, valve-controlled connections between each of said compression chambers and said rotor chamber, and means controlled from said shaft for successively operating said valve-controlled connections to admit the fired gas to said rotor chamber.

2. In a gas turbine engine, in combination, a casing having therewithin a rotor chamber and provided at opposite sides of said chamber with a series of compression chambers separate from said rotor chamber, a piston for each of said compression chambers, a shaft within said casing extending through said rotor chamber, a rotor member fixedly mounted upon said shaft and within said rotor chamber, cam wheels carried by said shaft at opposite sides of said rotor chamber, with operative connections between said cam wheels and said pistons constructed and arranged to reciprocate said pistons with the rotation of said shaft and to successively compress charges in successive compression chambers, means for successively firing gas compressed in said chambers, and valve-controlled connections between each of said compression chambers and said rotor chamber, with means controlled from said shaft for successively operating said connections to admit the fired gas to said rotor chamber.

3. In a gas turbine engine, a casing, a shaft journaled therein and extending longitudinally and interiorly thereof, compression chambers within said casing spaced longitudinally thereof, an expansion chamber within said casing separated from and intermediate said compression chambers, rotor members fixedly mounted on said shaft within said expansion chamber, firing electrodes associated with said compression chambers, means for feeding fuel to said chambers, means operated from said shaft and within said casing for compressing charges of fuel in said chambers, and valve-controlled means for conducting the fired charge into said expansion chamber and against the adjacent rotor member therein.

4. In a gas turbine engine, in combination, a casing provided with a rotor chamber therein and with a plurality of compression chambers and complemental communicating explosion chambers, valve controlled gas inlet passages communicating with said compression chambers, a piston for each compression chamber, a shaft journaled in said casing and extending in said rotor chamber, a rotor member fixedly carried by said shaft within said rotor chamber, a disk fixedly carried by said shaft within said casing and without said rotor chamber, said disk being provided with a cam face, operative connections between said cam face and said pistons arranged to operate said pistons to successively charge and compress gas in successive compression and explosion chambers, means for successively firing gas compressed in successive explosion chambers, valve controlled connections between each of said explosion chambers and said rotor chamber, and means controlled from said shaft for successively operating said

connections to admit the fired gas to said rotor chamber.

5. In a gas turbine engine, a casing, a shaft journaled in said casing and extending longitudinally and interiorly thereof, two series of compression chambers within said casing spaced longitudinally thereof, an expansion chamber within said casing separate from and intermediate said spaced series of compression chambers, reciprocating pistons for each of said compression chambers, rotor members carried by said shaft within said expansion chamber, cam disks carried by said shaft without said expansion chamber, means for feeding fuel to said com-

pression chambers, operative connections between said cam disks and said pistons for successively compressing charges of fuel within said compression chambers, firing electrodes associated with said compression chambers and valve-controlled means operated from said shaft for successively conducting the fired charges from said compression chambers into said expansion chamber and against the adjacent rotor member 25 therein.
